United States Patent Office

Des. 213,607
Patented Mar. 18, 1968

213,607

SUPPORT FRAME FOR SIGNBOARDS OR THE LIKE

James B. Grady, Delhi Township, Hamilton County, Ohio
(504 Overhill Lane, Cincinnati, Ohio 45238)

Filed Sept. 18, 1967, Ser. No. 8,629

Term of patent 14 years

U.S. Cl. D96—12
Int. Cl. D20—03

fig 5

fig 6

FIG. 1 is a perspective view of a support frame for signboards or the like showing my design.

FIG. 2 is a side elevational view thereof.

FIG. 3 is an elevational view taken from one end thereof.

FIG. 4 is a reverse side elevational view thereof from the side opposite that shown in FIG. 2.

FIG. 5 is a top plan view thereof.

FIG. 6 is an elevational view thereof taken from the end opposite that shown in FIG. 3.

The broken lines shown in FIG. 1 are for the purpose of illustration of use only.

I claim:

The ornamental design for a support frame for signboards or the like, substantially as shown and described.
